UNITED STATES PATENT OFFICE.

FERNAND E. D'HUMY, OF ENGLEWOOD, NEW JERSEY, ASSIGNOR TO RAMP BUILDINGS CORPORATION, OF NEW YORK, N. Y., A CORPORATION OF DELAWARE.

BUILDING.

Application filed November 28, 1925. Serial No. 71,959.

This invention relates to garage buildings of the type having storage floors located at different levels and connected by ramps over which the automobiles may be driven under 5 their own power from floor to floor in order to reach their respective storage spaces. An object of the invention is to provide in such a garage, a floor and ramp arrangement providing an easy ascent grade between the floors without reducing the storage capacity of the building.

A further object is to provide a storage building having an ascending spiral ramp upon opposite sides of which are arranged 15 groups of superposed storage floors. The floors of the two groups are located at staggered levels and have driveway connections with the spiral ramp at spaced points in its height.

20 In the drawings Fig. 1 is a horizontal section taken on the line 1—1 of Fig. 2;

Fig. 2 a vertical section taken on the line 2—2 of Fig. 1;

25 Fig. 3 a vertical section taken on the line 3—3 of Fig. 1;

Fig. 4 a view similar to Fig. 3 on a reduced scale, showing the spiral ramp and the floors diagrammatically;

30 Fig. 5 a section taken on the line 5—5 of Fig. 1;

Fig. 6 a section taken on the line 6—6 of Fig. 1;

35 Fig. 7 a horizontal section taken through a modified form of building; and

Fig. 8 a section taken on the line 8—8 of Fig. 7.

The building, in the present instance, has a rectangular plan and is formed with side walls 1 and 2 and end walls 3 and 4. A 40 partition wall 5 is disposed in a vertical plane midway between the side walls 1 and 2 and divides the building plan into two equal areas. This partition may be an open structure instead of a closed wall. Located 45 at opposite sides of the partition wall 5 are two groups of superposed storage floors 6 and 7, respectively. The floors 7 are arranged in planes intermediate the planes of the floors 6.

50 Located at the center of the building is a continuous, ascending spiral ramp 8. This ramp extends equal distances into the areas of the floors 6 and 7 at opposite sides of the central partition and leads from the ground floor upwardly through the floors 6 and 7.

The pitch or inclination of the ramp is such that it describes one complete circle within a distance equal to the space between a pair of the superposed floors 6 or 7. One half of each turn of the ramp is located within 60 the area of the floors 7 and the other half is located within the area of the floors 6. The ramp extends through the floors 6 and 7 at points located upon the diametrical line 6—6 extending at right angles to the partition 5, 65 as shown in Fig. 1. The points of intersection of the ramp with the floors 6 and 7 are located midway between the division plane and the opposite side walls 1 and 2.

Each of the floors 6 is laid out to provide 70 a driveway or corridor space 9 extending parallel to the partition 5 throughout the length of the floor. At opposite sides of the driveway 9, arranged along the side wall 1 and the partition 5, are rows of individual 75 storage spaces 10 for receiving the automobiles. Each floor 7 is similarly laid out to provide a driveway or corridor space 11 and storage spaces therealong. The driveways 9 and 11 extend substantially tangential to 80 the opposite sides of the spiral ramp and cross the ramp at its points of intersection with the floors 6 and 7. The driveways make connection with the spiral ramp over short ramps 12 and 13. The ramps 12 lead 85 downwardly from the floors to the ramp, and the ramps 13 lead upwardly from the floors to the ramp, as shown in Fig. 5. These short ramps are formed so as to merge the floors 90 evenly with the ramp around the curved contour thereof and provide driveway connections between the floors and the ramp over which the cars may be driven. A doorway leads through the end wall 4 to one end 95 of the driveway 11 of the ground floor.

Within the space defined by the spiral ramp is a group of superposed central storage floors 14. Each of the floors 14 is laid out to provide a number of individual automobile storage spaces 15 which open outwardly toward one side of the ramp 8. The floors 14 are upon the same level as the floors 7 and are in effect a continuation thereof. Short driveway inclines or ramps 16 and 17 connect each floor 14 with the 100 spiral ramp. The inclines 16 lead upwardly from the floors to the ramp and the inclines 17 lead from the floors downwardly to the ramp.

105 The spiral ramp is supported by outer col- 110

umns 18 and inner columns 19, and by its connections with the floors and with the partition 5. Along its inner and outer edges the spiral ramp is provided with a curbing 5 20. This curbing is omitted at the points where the ramp has its driveway connections with the various floors. The spiral ramp structure is, therefore, laterally open so that the driver of an ascending or descending car 10 may look clear across the floors 14 and between the columns 19 to the opposite side of the ramp and observe traffic conditions for a considerable distance ahead of him. He may also look over the curbing to the 15 various storage floors as he approaches them and observe if there is a car entering the ramp from one of the floors.

In Figs. 7 and 8 is shown a modified arrangement of the central floors surrounded 20 by the spiral ramp. In this case the partition extends across the enclosed central space in the form of an open structure and two groups of superposed floors 21 and 22 are located in said space at opposite sides of 25 the partition. The floors of the group 21 are located upon the same levels as the floors 7, while the floors of the group 22 are upon the same levels as the floors 6. The floors of 30 the two groups connect with opposite sides of the spiral ramp over short, oppositely inclined ramps 23 and 24 similar to the ramps 16 and 17 of the previously described form.

It will be seen from the foregoing that the 35 combination of the staggered storage floors with the continuous, spiral ramp provides an easy ascent grade through the building with a minimum sacrifice of storage space. The easy ascent grade and the open structure 40 at the center of the building enable the cars to be driven quickly and safely to the various floors. While the spiral ramp structure is shown in both forms of the invention as having a circular form in plan, it will be understood that it may be made oval or 45 in any convenient form.

What I claim is:

1. A garage building comprising two 50 groups of superposed floors arranged side by side with the floors of one group intermediate the planes of the floors of the other group; an inner helical driveway for inter-floor travel ascending continuously from end to end thereof from the lowermost floor of 55 the building and rising through both groups of floors; ramps connecting the floors of each group with the outer edge of said helical driveway; and ramps connecting the floors of each group with the inner edge of said 60 helical driveway, said driveway being of such radius and so located with reference to 65 said two groups of floors as to have a low grade and to intersect the floors of the two groups a sufficient distance from the adjacent edges of the groups of floors to afford

car-storage spaces on the floors within the turns of the driveway.

2. A garage building comprising outer walls; two groups of superposed level floors located at opposite sides of a vertical division plane with the floors of one group lying in planes intermediate the planes of the floors of the other group; a continuously ascending helical driveway structure rising through both of said groups of floors from 70 the lowermost floor level of the building and intersected by said division plane, those sections of the several convolutions of the continuous helical driveway structure at each side of said division plane passing through 75 those floors located at the same side of the plane as said sections at points substantially midway the ends of said sections; and two short ramp connections between each floor and the section of the helical driveway structure which intersects the floor, leading respectively downwardly and upwardly from 80 said section to the floor at opposite sides of the line of intersection of the helical driveway structure section with the floor. 85

3. A garage building comprising outer walls; two groups of superposed level floors located at opposite sides of a vertical division plane with the floors of one group lying in planes intermediate the planes of the floors of the other group; a continuous helical driveway structure rising through both of 90 said groups of floors and intersected by said division plane, those sections of the several convolutions of the helical driveway structure at each side of said division plane passing through those floors located at the same side of the plane as said sections at points substantially midway the ends of said sections; and two short ramp connections between each floor and the section of the helical driveway structure which intersects the floor, leading respectively downwardly and upwardly from 95 said section to the floor at opposite sides of the line of intersection of the helical driveway structure section with the floor. 100

4. A storage building comprising two groups of superposed floors, the floors of one group being arranged in laterally offset relation with respect to the floors of the other group and in planes intermediate the planes of the floors of said other group, a continuous inter-floor driveway rising through both groups of floors and intersecting floors of the two groups alternately, each floor having storage area thereon and two separated 110 unobstructed intra-floor driveway portions 115

120

thereon each extending past storage area on the floor, said inter-floor driveway entering and leaving each floor between the adjacent ends of said two intra-floor driveway portions of the floor, and ramps merging the adjacent ends of the two intra-floor driveway portions on each floor with the interposed section of the inter-floor driveway to form a continuous driving corridor on each floor.

5. A storage building comprising two groups of superposed floors, the floors of one group being arranged in laterally offset relation with respect to the floors of the other group and in planes intermediate the planes of the floors of said other group, means forming two reversely curved driveway connections between each floor of one group and the next higher and lower floors respectively 15 of the other group, said driveway connections merging at their ends with the floors connected thereby, and two ramps merging two outer edge portions of each of said curved driveway connections with the two 20 floors connected thereby at points adjacent opposite ends of the curved driveway connection.

25 6. A storage building comprising two groups of superposed level floors located at 30 opposite sides of a vertical division plane

with the floors of one group lying in planes intermediate the planes of the floors of the other group; a continuously ascending helical driveway structure of uniform radius and uniform grade throughout rising 35 through both of said groups, intersected by said division plane and intersecting each floor of each group at a point substantially midway its points of intersection with the division plane, the outer curved edge of the 40 helical driveway being exposed and unobstructed for a material portion of its length adjacent each of said floor intersections and the floors at opposite sides of the division plane being provided with straight driveways with their inner and outer longitudinal edges extending in directions substantially tangential to the inner and outer curved edges, respectively, of the helical driveway at the points of floor intersection 45 and including between them the said exposed and unobstructed outer curved edge sections of the helical driveway; and ramps connecting said tangential driveways with the said exposed and unobstructed edge sections along 50 the curvature thereof.

55 In testimony whereof I hereunto affix my signature.

FERNAND E. D'HUMY.
